UNITED STATES PATENT OFFICE.

JOHN P. YOUNGMAN, OF HAZLETON, PENNSYLVANIA.

PORTABLE RANGE.

SPECIFICATION forming part of Letters Patent No. 363,786, dated May 24, 1887.

Application filed September 30, 1886. Serial No. 215,008. (No model.)

To all whom it may concern:

Be it known that I, JOHN P. YOUNGMAN, of Hazleton, in the county of Luzerne and State of Pennsylvania, have invented new and useful Improvements in Portable Ranges, of which the following is a full, clear, and exact description.

The invention consists of the construction, arrangement, and combination of parts, all as hereinafter described and claimed.

Reference is to be had to the accompanying drawings, forming a part of this specification, in which similar letters of reference indicate corresponding parts in both the figures.

Figure 1 is a sectional elevation of a portable range having my invention applied thereto, and Fig. 2 is a detailed sectional view showing a modification.

A represents the oven of the range; B B, the smoke spaces; C, the door to the oven, and D the pipe leading from the upper smoke-space to the chimney E. The oven A is connected to the heat passage or drum F by an opening, G, in which is fitted a damper, H. Leading from the heat passage or drum F is the pipe J, which conducts the heat from the oven to an upper story in the building. In this instance I have shown the pipe J surrounding the pipe D to save the heat radiated from said pipe; but it may be separate from the pipe D, if desired.

In the door C is formed an opening, K, to admit cold air to the oven A, and over this opening is placed a slide, L, for closing said open-

ing. The heat passage or drum F is by preference made of curved pipe, as shown in Fig. 1, 35 one end being placed upon the flange d of the opening G of the oven, the other being placed upon the flange d' of the opening h in the pipe J, so that the pipe forms a direct conduit for the heat from the oven to the pipe J. In place 40 of a curved pipe, as shown in Fig. 1, I may use two stove-pipe elbows placed together, as shown in Fig. 2; but I prefer the curved pipe, as shown in Fig. 1.

When the oven is used for baking, the 45 damper H and slide L will be closed; but when not used for baking the damper and slide will be opened, so that air will be heated in the oven and will pass to the pipe or drum F, and thence through the pipe J to the room above, 50 for warming the same.

Having thus fully described my invention, I claim as new and desire to secure by Letters Patent—

A portable range having an opening, G, at 55 the back communicating with the oven, said opening being provided with a damper, H, in combination with the pipe D, pipe J, surrounding the pipe D, and the pipe F, connecting the opening G with the pipe J, an opening, K, being formed at the front of the oven for the admission of air, substantially as described.

JOHN P. YOUNGMAN.
